ASSEMBLING MECHANISM FOR TYPOGRAPHICAL COMPOSING MACHINES

Paul Hilpman, Garden City, N. Y., assignor to Mergenthaler Linotype Company, a corporation of New York

Application May 11, 1953, Serial No. 353,957

3 Claims. (Cl. 199—27)

This invention relates to typographical composing machines, such as "Linotype" machines, wherein circulating matrices and expandable spacebands are composed in line in an assembling elevator under the influence of a constantly rotating starwheel. After a line is completely composed, the elevator is raised to position the line between a pair of depending fingers of a spring actuated delivery slide which thereupon moves to the left in order to shift the composed line from the assembling elevator into a line transporter or so-called "first elevator," and at the same time inaugurate the operation of the machine.

In these machines, the spacebands are stacked in a storage box disposed above the assembling elevator and, when released, pass downwardly through a vertical chute into the path of the rotary starwheel which advances them in a facewise or lateral direction into the receiving end of the assembling elevator and against the tension of a line resistant finger attached to an assembler slide. The matrices also, when released, are directed into the path of the rotary starwheel and are advanced into the assembling elevator in similar fashion.

While the above arrangement has served its purpose for many years, it nevertheless frequently happens, during rapid composition, that the matrices and spacebands (particularly the latter) upon entering the assembling elevator fail to seat properly therein upon their respective horizontal supporting rails. As a result, further composition must be suspended until the disturbance is rectified. The above condition becomes more serious in modern high speed machines which are operated automatically by tape controlled mechanism such as that represented by the well known "Teletypesetter." For example, if the longer and thicker wedge shaped member of a descending spaceband should fail to reach its proper position in the elevator, it may and usually does not only retard or prevent the entry thereinto of following matrices but, in addition, and due to its protrusion above the elevator, may positively stop the upward movement of the latter before it arrives at the line delivery station. In the first instance, and because of the absence of the last matrix or matrices that should have been composed, an imperfect slug would be produced during the machine cycle and eventually have to be replaced. In the second instance, the offending spaceband probably would be damaged and likewise have to be repaired or discarded. Moreover, in these automatically operated machines, and through the failure of the assembling elevator to arrive at the line delivery station, the delivery slide would not be released to perform its normal line transfer function and the elevator then would be allowed to drop of its own weight until abruptly arrested by a stop element positioned beneath it. As a result, at least part of the composed line is jarred or shaken from the elevator and spilt over the floor.

The present invention is intended to obviate the above and other difficulties, and to this end the rotary starwheel is so mounted that, as a line is being composed or stacked in the elevator, it will be capable of overrunning its

2

driving spindle under the impact of a descending spaceband or matrix, if the timing so requires.

In the accompanying drawings, the invention has been shown merely in preferred form and obviously many changes and variations may be made therein which still will be comprised within its scope. It therefore should be understood that the invention is not limited to any specific form or embodiment except insofar as such limitations are specified in the appended claims.

10 Referring to the drawings:

Fig. 1 is a perspective view showing part of the assembling mechanism, including the driving pulley for the inclined assembler belt, a portion of the assembling elevator, the rotary starwheel, and the spaceband box disposed above and in operative relation thereto;

15 Fig. 2 is a front elevation showing, on an enlarged scale, the improved starwheel mounting, the receiving end portion of the assembling elevator, and indicating by the dotted lines the driving means for the starwheel;

20 Fig. 3 is a vertical section taken on the line 3—3 of Fig. 2;

Fig. 4 is a vertical section taken on the line 4—4 of Fig. 3; and

25 Fig. 5 is a detail perspective view of the assembler chute block.

As best shown in Figs. 1 and 2, the matrices *x* and spacebands *y*, after being released from their respective places of storage by operation of a keyboard (not shown), are composed in line in an assembling elevator 2 under the influence of a constantly rotating starwheel 3 and against an upstanding line resistant finger 4 of a horizontal assembler slide 5. Upon release, the matrices *x* are directed vertically downward through adjacent channels of a partitioned front plate 6 onto an inclined delivery belt 7 and thence over a curved chute block 8 into the rotary path of the starwheel 3. The spacebands *y* are contained in a storage box 9 and, when released, are adapted to drop endwise through a vertically disposed chute 9a depending from the storage box and terminating directly above the starwheel 3 in spaced relation thereto. As the matrices *x* and spacebands *y* are caused to enter the assembling elevator 2 under the stacking influence of the starwheel 3, they obtain the necessary support therein by the engagement of their projecting ears with corresponding supporting rails on the front and rear side walls 45 of the elevator.

The starwheel 3 (Figs. 2 and 4) is mounted as usual on the front end portion of a fore-and-aft spindle 10 and presents four radial equidistantly spaced arms 3a for stacking the matrices and spacebands, in the order of their release, into the receiving end of the assembling elevator 2.

As best shown in Fig. 3, the spindle 10 is rotatably mounted in a bearing thimble 11 of the front plate 6 and is driven by a gear 12 through the medium of a friction clutch which includes a pair of spaced-apart disk-like members 13a and 13b slidably mounted by means of a D-shaped key connection on a rearward extension 10a of the spindle. Adjacent the rear face of the front plate 6, the bearing thimble 11 is formed with a head portion 11a presenting an annular bearing surface whereon the driving gear 12 is rotatably mounted. The gear 12 is formed with a hollow hub portion 12a drilled through to accommodate the rearward extension 10a of the spindle and having an inside dimension large enough to accommodate the disk-like member 13a of the friction clutch. A stop shoulder 10b, formed on the spindle 10 and located flush with the rear face of the bearing thimble 11, serves not only to locate the clutch member 13a longitudinally on the spindle but also serves, through said member, to prevent endwise displacement of the spindle in a forward direction. Any endwise displacement of the spindle in

a rearward direction is prevented by a collar 10^c formed thereon and engaging the front end of the bearing thimble 10.

The rear clutch member 13^b is held frictionally engaged with the rear face of the gear hub portion 12^a by a compression spring 14 seated against a thumb screw 15 and which also holds the forward face of the hub portion frictionally engaged with the forward clutch member 13^a. The thumb screw 15 (Fig. 3) is threaded into the free end of the rearward extension 10^a of the spindle 10 so as to be capable of adjustment to regulate the tension of the clutch spring 14 according to the resistance normally presented to the starwheel 3 during composition.

So far as described, the parts, their construction and mode of operation are or may be the same as embodied in the commercial Linotype machines.

The present invention, as previously stated, is directed to means whereby the rotary starwheel 3 is capable of running ahead of the driving spindle 10 under the impact of either a descending spaceband after its release from the storage box 9 or an approaching matrix as it is directed by the chute plate 8 into the rotary path of the starwheel. In the preferred embodiment illustrated, the spindle 10, as shown in Figs. 2 and 3, is formed with a forward cylindrical bearing portion 10^d upon which the starwheel 3 is rotatably mounted. Said bearing portion is slightly reduced in diameter so as to present a shoulder 10^e for locating the starwheel in properly spaced relation to the front plate 6 before mentioned. At its front end, the spindle 10 is also provided with a ratchet wheel 10^f which is securely fastened thereto and which is housed within a relatively large recess 3^b formed in the front face of the starwheel 3. The required driving connection between the pinion 10^f and the starwheel 3 is established by a pawl 16 pivoted to the starwheel at the bottom of the recess 3^b and held normally engaged with the ratchet wheel 10^f by a light spring 16^a. Thus it will be seen that, while the starwheel 3 will positively be driven in the proper direction to perform its regular stacking function, it also will be permitted to overrun its normal rotational speed whenever it is subjected to the impact of the falling matrices or spacebands during line composition.

The action of the parts will be clear from Fig. 2 which shows a falling spaceband as it is intercepted by one of the arms of the starwheel, a bad timing condition which frequently leads to trouble. When the starwheel is made fast to its driving spindle, the spaceband does not descend far enough to be advanced properly into the assembling elevator by the following arm of the starwheel. When, however, the starwheel is free to rotate ahead of the driving spindle, as herein, the spaceband will be free to continue its descent and be forced into

the elevator either by the arm which immediately follows or one of the other following arms—all depending upon the speed of travel of the spaceband in relation to the speed of rotation of the starwheel and the position of the arms of the starwheel at the time. Once the spaceband and the starwheel attain normal speed, the pawl and ratchet coupling becomes immediately active and the spaceband will be forced into the elevator in the normal way and against the tension offered by the line resistant finger.

The pawl and ratchet coupling is especially advantageous in carrying out the invention, since there is no limitation placed upon the free-wheeling of the starwheel and yet the driving connection will be immediately restored once the proper timing of the parts has been established by the parts themselves.

What is claimed is:

1. Assembling mechanism for typographical machines equipped with gravitational matrices and expandable spacebands, including, in combination, a constantly rotating starwheel formed with a plurality of radial arms, a driving spindle therefor, an assembling elevator wherein the matrices and spacebands are composed in line under the influence of the starwheel, and a pawl and ratchet free-wheeling driving coupling between the starwheel and the driving spindle whereby the starwheel is capable of turning about its axis in the direction of rotation of the spindle under the impact of a falling spaceband or matrix, said ratchet having a substantially greater number of teeth than there are arms on the starwheel, and said pawl being normally engaged with the ratchet to prevent the starwheel from turning about its axis in a direction opposite to the direction of rotation of the spindle.
2. A combination according to claim 1, wherein said coupling includes a ratchet wheel secured to the spindle, and a spring pressed pawl attached to the starwheel and normally engaged with the ratchet wheel.
3. A combination according to claim 2, wherein the ratchet wheel and the pawl are housed within a recess formed in the starwheel.
